Primary Examiner — Mitchell I. Siegel

(57) **CLAIM**

The ornamental design for a golf club head, as shown and described.

DESCRIPTION

FIG. 1 is a front perspective view of a golf club head according to a first embodiment;

FIG. 2 is a rear perspective view of the golf club head of FIG. 1;

FIG. 3 is a front elevational view of the golf club head of FIG. 1;

FIG. 4 is a rear elevational view of the golf club head of FIG. 1;

FIG. 5 is a top view of the golf club head of FIG. 1;

FIG. 6 is a bottom view of the golf club head of FIG. 1;

FIG. 7 is a left side view of the golf club head of FIG. 1;

FIG. 8 is a right side view of the golf club head of FIG. 1;

FIG. 9 is a front perspective view of a golf club head according to a second embodiment;

FIG. 10 is a rear perspective view of the golf club head of FIG. 9;

FIG. 11 is a front elevational view of the golf club head of FIG. 9;

FIG. 12 is a rear elevational view of the golf club head of FIG. 9;

FIG. 13 is a top view of the golf club head of FIG. 9;

FIG. 14 is a bottom view of the golf club head of FIG. 9;

FIG. 15 is a left side view of the golf club head of FIG. 9; and,

FIG. 16 is a right side view of the golf club head of FIG. 9. The broken lines shown on the drawings form no part of the claimed design.

1 Claim, 8 Drawing Sheets
